UNITED STATES PATENT OFFICE.

JOHN A. CLARK, OF YANKEE HILL, CALIFORNIA.

GOLD-SAVING APPARATUS.

No. 801,968.

Specification of Letters Patent.

Patented Oct. 17, 1905.

Application filed August 1, 1904. Serial No. 219,041.

To all whom it may concern:

Be it known that I, JOHN A. CLARK, a citizen of the United States, residing at Yankee Hill, in the county of Butte and State of California, have invented new and useful Improvements in Gold-Saving Apparatus, of which the following is a specification.

My invention relates to improvements in gold-saving apparatus for use particularly in hydraulic and other placer mines.

This invention consists of parts and the combination of parts, which will be more fully explained by reference to the accompanying drawings, in which—

15 Figure 1 is a side elevation, partly in section, of my invention. Fig. 2 is a section of a portion of a table, showing screen-frame and locking means therefor. Fig. 3 is a side elevation of same. Fig. 4 is a plan view of 20 a sluice and a set of tables. Fig. 5 is a longitudinal section of sluice, showing operating-levers for grizzly-gate. Fig. 6 is a side elevation, partly in section, of table and vibrating screen. Fig. 7 is a cross-section of same.

25 A represents a sluice-box carrying the rocks, boulders, and earth just as they come from the mine under the impetus of perhaps several hundred inches of water. Interposed in the bottom of this sluice is a grizzly or grating 2, comprising a series of parallel-spaced iron bars extending lengthwise of the sluice, through which the sands, gravels, and material less than a certain size, together with some water, are discharged into suitable 30 hoppers 3 and directed thence to opposite sides upon the aprons 4 and from there upon the tables 5.

In order to regulate the amount of discharge through the grizzlies or grizzly-sections, (for preferably the grizzly is made in sections, as here shown,) I provide a hinged grating 6, pendent beneath a section of the grizzly and adapted to be folded up in the direction of the current-flow to close the inter-spaces of the grizzly. This grating or closure 45 is preferably formed of iron or steel bars, substantially A-shaped in cross-section and staggering with the bars of the grizzly. It may be operated by any suitable means, as the 50 levers 7 and links, rods, or chains 8, connecting with the free end of the grating. The levers are fulcrumed above sluice A, and the rods 8 pass down through the grizzly near the side of the sluice-box. By pressing down 55 on the lever the grating is raised to close the corresponding grizzly-apertures and to a

great extent if not quite cut off the passage of material and water therethrough. The closure is held in lifted position by any retaining means—as, for instance, the hook 9, 60 engaging lever 7. Each section of the grizzly might be provided with a similar closure. By this construction it is possible to regulate the amount of water and material for the tables and to cut off discharge to any set of 65 tables for purpose of clean-up without shutting down the mine, as results when the water in sluice A is turned off.

The tables 5 may be of any number. Preferably they are in series, as here shown, one 70 above the other, oppositely inclined and each adjustable vertically in suitable guides in a framework 10.

I have illustrated the tables as having an underneath cross-bar 11 at each end, the ends 75 of the cross-bars being movable in the vertical guides 12 and supported on pins 13, passing through perforations in the guides. Thus either end of a table may be raised or lowered to vary the pitch. The tables may be 80 of any length or width and are divided longitudinally into a plurality of sluices or runways by shallow partitions 14.

The surface of a table is rifled or covered with canvas, as shown at 15, Fig. 2, and over 85 this canvas is stretched metal screening or fine wire-netting 16, which has been found to possess the quality of retarding the velocity of the undercurrent and to assist materially the separation of the sands and values from the 90 gangue and coarse barren matter. However, in order to prevent the sands packing at any one place to abnormal depths, and so to a degree destroying the efficiency of the screening, it is preferred that the screen be secured 95 on all sides. When a clean-up is necessary, the screen is taken up and the canvas swept and washed off.

As it is necessary to clean up every few hours, it is essential that means be provided 100 for quickly taking up and putting down the screens. Consequently the screen is arranged in sections of a width equal to that approximately of the concentrating-surface between the partition 14 and of such length easily to 105 be handled. I have found that two and a half or three feet is a good length for these sections. Each section is framed in a metal frame and each frame is adapted to be removably locked in its place on the table. These screen-frames comprise two lower side plates 17 and two upper side plates 18, between which two

opposite edges of a screen-section are bolted. The plates 18 have each an inside drop portion 19 overhanging the inner edge of its respective plate 17 and adapted to bring the screen flush with the under side of the plates 17, so that the screen will lie flat on the canvas. The upstream and downstream edges of the screen are bolted to the under side of the thin cross-plates 20, which are suitably secured to the plates 18. A screen-section is quickly taken out of its frame by removing the plates 17 and unbolting the screen from the cross-plates 20. The frames are laid on the canvas one after another and are removably held in position by suitable means, as the locking devices 21, which consist of levers fulcrumed in the parts 14, adapted when vertical to press on the sides of the frames and prevent any movement of the latter. To take out a screen-frame or to replace a torn screen or a bad section of canvas, it is only necessary to give the levers 21 a knock to one side and both the screen-frame and canvas are loosened, since the canvas is held in position by the frames and their locking means. With these screens thus framed and arranged in sections it is an easy matter to take them up and lay them down, and the work is done rapidly, and no injury results to the screens or the canvas on the tables, as where there is frequent tacking, nailing, and the like.

It has been found that by using a series of superposed oppositely-inclined tables, as here shown, each provided with removable screens, a very complete separation of the sands and values is effected and the saving of the fine gold becomes very near if not quite perfect. Each runway of a table is provided at its discharge end with a curved splash-plate or hopper 21^a, which directs the water and material into the corresponding runway of a succeeding lower table, but does not interfere in any way with the raising and lowering of the latter. The passage of the water from one runway to a succeeding one and in a reverse direction causes each time a turning over of the material and a succession of rearrangements of the particles, so that a most thorough washing and separation takes place.

Means must be provided whereby to vary the pitch of the tables according to the head of water or the character of the material undergoing treatment and to drop the tables down so as to permit the removal of the screens, since the tables are normally disposed compactly one above the other. The raising and lowering of the tables may be accomplished by a variety of means. I have illustrated a lever 22, fulcrumed on the frame above the tables, as at 22', with the weight end of the lever disposed about midway of the length of the tables. Rods 23 23' depend from the lever and are adapted to engage pins, hooks, or projections 24 on opposite ends and sides of each box. Thus to lift or

lower one end of a box the rods 23 would be engaged with pins 24 at that end. If the opposite end of a box was to be raised or lowered, the rods 23' would be engaged with the pins at that end, while if a box was to be raised or lowered bodily both sets of rods would be engaged, so that the box could be entirely suspended from the lever. Of course where the tables were very long or very heavy a lever could be disposed at each end, in which case it would require an operator at each lever where a box was to be moved bodily.

The final segregation and collection of the black sand and values passing beyond the tables is effected by sifting through a fine screen 25, mounted in a suitable spring-frame 26, disposed in an opening in the bottom of the lowermost table. It has been usual to try to sift these heavy wet sands by a horizontal reciprocating or shaking movement; but the more they are shaken in that manner the tighter they pack and cling to the screen. I have found that by vibrating the screen in a direction at right angles to its surface, alternately lifting and depressing it by sudden blows, the heavier sands and values are forced through, while the water and barren sands and gangue pass on over. The means for effecting this vibration is here shown as comprising a horizontal spring-arm 28, secured fast at one end and connected to the under side of frame 26, as shown in Figs. 6, 7, and adapted to be operated on by a ratchet-wheel 29. Any suitable means may be employed to rotate wheel 29. For convenience and economy the water running over the tables may be made to furnish the required power by interposing an overshot wheel 30 in the path of water-discharge from sluice 28. The shaft of wheel 30 carries a pulley 31, around which passes a belt or cord 32, running to a pulley on the shaft of ratchet 29. The motion imparted to wheel 30 by the body of water falling from sluice 27 is transmitted to the ratchet 30, which causes the arm 28 and connections 33 to be vibrated rapidly and a consequent vibratory motion or shock is given the frame 26 and its screen 25.

Having thus described my invention, what I claim, and desire to secure by Letters Patent, is—

1. In a gold-saving apparatus the combination with a sluice-box, and a grizzly in the bottom thereof and comprising a plurality of spaced bars extending in the direction of the current-flow, and a hinged closure for the grizzly said closure normally pendent beneath the grizzly and including bars extending in the direction of the current-flow and adapted, when the closure is moved upwardly about its hinge connection, to close the interspaces between the bars of the grizzly, whereby the flow of the current is diverted.

2. In a gold-saving apparatus the combination with a sluice-box, and a grizzly in the bot-

- tom thereof and comprising a plurality of spaced bars extending in the direction of the current-flow, and a hinged closure for the grizzly said closure normally pendent beneath the 5 grizzly and including bars extending in the direction of the current-flow and adapted, when the closure is moved upwardly about its hinged connection, to close the interspaces between the bars of the grizzly whereby the 10 flow of the current is diverted, means for raising and lowering the closure and means for holding the closure in its closed position.
3. In a gold-saving apparatus the combination with a sluice-box and a grizzly in the bottom thereof and comprising a plurality of spaced bars extending in the direction of the current-flow, a hinged closure for the grizzly said closure normally pendent beneath the grizzly and including bars extending in the 15 direction of the current-flow and adapted, when the closure is moved upwardly about its hinged connection, to close the interspaces between the bars of the grizzly whereby the flow of the current is diverted, a fulcrumed 20 lever and means connecting one end thereof with the closure, and a latch mechanism for securing the lever and holding the closure in its closed position.
4. In a gold-saving apparatus the combination with a sluice-box of a grizzly in the bottom of said sluice-box said grizzly comprising a plurality of bars extending in the direction of the current-flow, and a hinged closure for said grizzly, said closure pendent beneath the grizzly, and comprising a grating having 25 bars staggered relative to the bars of the grizzly, a lever fulcrumed above the grizzly, connections between the lever and the free end of the grating and means for locking the lever and holding the grating in a closed position.
5. In a gold-saving apparatus the combination with a table having partitions and a concentrating-surface, of a screen overlying said 30 surface and comprising screen-plates and frames therefor having upper and lower plates

between which the edge of said screen-plate is fitted said partitions interposed between adjacent frames and said upper plate having a drop portion overhanging the inner edge of 50 the lower plate and adapted to position the screen-plate substantially flush with the under side of the lower plate, and levers fulcrumed to the partitions and having one portion bear upon the upper plate and thereby lock the 55 screen-frames in position.

6. In a gold-saving apparatus the combination of a table having vertical partitions, a concentrating-surface on the table, a sectional screen overlying the concentrating-surface, 60 each of said screen-sections having a frame which includes upper and lower plates between which the edge of the screen-plate is received said upper plate having a drop portion overhanging the inner edge of the lower 65 plate and adapted to position the screen-plate substantially flush with the under side of the lower plate, one of said partitions interposed between the adjacent edges of each pair of frame-plates, cross-plates secured to the drop 70 portions of the upper frame-plates, and levers fulcrumed upon the partitions and having their lower ends adapted to engage the upper frame-plates to lock the frames in place.

7. In a gold-saving apparatus the combination with a sluice and a concentrating-table upon which the sluice delivers, of a screen-frame on the table and comprising upper and lower side plates between which the screen is 75 removably clamped, said upper plates having drop portions extending over and beyond the inner edge of the lower plates and rigid connections between the plates on the opposite sides of the frame, and means for securing 80 the screen to these connections.

In testimony whereof I have hereunto set my hand in presence of two subscribing witnesses.

JOHN A. CLARK.
